CLAIM

The ornamental design for a tool for dispensing adhesives, sealants, and underfill materials, as shown and described.

DESCRIPTION

FIG. 1 is an elevational view of a first end for the new design for a tool for dispensing adhesives, sealants, and underfill material;

FIG. 2 is a top plan view of the tool as shown in FIG. 1;
FIG. 3 is a bottom view;

FIG. 4 is a left side elevational view of the tool as shown in FIG. 1, wherein the back elevational view is a mirror image; and,

FIG. 5 is a right side elevational view.
